AIRCRAFT COOLING VALVE

Jesse E. Eshbaugh and Nelson Walker, Flint,
Mich., assignors to General Motors Corporation,
Detroit, Mich., a corporation of Delaware

Application December 28, 1944, Serial No. 570,149

5 Claims. (Cl. 277—61)

1

This invention relates to an improved heat transfer system and more particularly to a pressure control valve especially adapted for the liquid cooling system of an airplane engine.

The operating temperature of an engine is a factor for reliability and performance and the efficiency of the cooling system is raised by closing the interior from atmosphere and utilizing the heat expansion of the contents to place the circulating liquid under pressure. Thus the boiling point of the liquid can be increased and evaporation reduced and more heat can be absorbed in the engine jacket and dissipated in the radiator. To prevent bursting strain on the parts the practice has been to close the system through the use of an ordinary pressure relief valve held on its seat by a yielding spring whose force is overcome to unseat the valve when the internal pressure exceeds by a predetermined value the external or atmospheric pressure on the valve. Since atmospheric pressure varies considerably between sea level and the higher altitudes at which certain planes now fly the conventional pressure valve set to maintain a given pressure at sea level will blow off unfortunately at a much lower pressure in altitude flight or just when heat dissipation in the radiator is dependent on a relatively smaller air density and calls for increased pressure on the contents.

To meet the situation the present invention involves the provision of an automatic control valve responsive to pressure differential but which is compensated for differences both in altitude and system temperature.

In the accompanying drawing showing the control device in elevation and partly in section the reference numeral 1 indicates a cooling system wall for the space or passageway 2 to contain the cooling liquid which circulates between the engine cooling jacket and the radiator. On the wall 1 is a threaded boss 3 to receive the reduced end or nipple 4 of the hollow casing 5 of the control unit. Interiorly of the casing is a shoulder 6, preferably having a raised annular rib affording a valve seat for an inwardly seating or outwardly opening valve and when the valve is open the hollow casing 5 provides a passageway for communicating the interior of the system with the exterior atmosphere through the reduced end portion 4 and an opening in the casing wall desirably in the form of a hollow lateral extension 7 to which may be joined a hose or tubing leading to a convenient vent point.

By-passing the main valve to relieve sub-atmospheric pressure within the system is a pas-

2

sage conveniently formed in the wall of the casing 5 and normally closed by an inwardly opening check valve 8. For the purpose of the by-pass the casing wall has an enlargement or thickened portion 9 containing drilled openings 10 and 11 with the lateral opening 10 entering the casing port below the valve seat 6 and being closed at its outer end by a plug 12 and the vertical opening 11 joins the hole 10 with a pocket 13 housing the outwardly seated valve 8 and its spring 14. The valve seats against a ring of rubber, fiber or other suitable material secured by a hollow rivet 15 on the underside of a partition wall or flat plate 16 which extends entirely across the top of the casing 5 under the removable cover or dome 17. One or more holes can be drilled through the partition 16 to open the interior of the cover to atmospheric pressure within the casing 5.

A central opening in the partition 16 receives an axially extending dependent pin 18 threaded at its upper end for adjustable attachment with a collar or abutment head 19 which bottoms on the upper side of the partition 16 and seats one end of a coil spring 20 whose opposite end is located within and by the raised central portion of the domed cover 17. A set screw 21 removably threaded into the top of the dome projects downwardly and limits upward movement of the pin 18 in its deflection of the spring 20. Removal of the set screw 21 enables insertion of a screw driver into engagement with the slotted upper end of the pin 18 for its adjustment in the stop collar 19 to vary the length of the pin projection downwardly below the wall 16 and thereby control to a predetermined extent the relative movement of the valve parts before the spring 20 comes into action to resist further movement. The upper end of the collar 19 is slotted as at 22 to permit the collar to be pinched inwardly and contracted into tight frictional contact with the pin for insuring against accidental turning of the pin relative to the stop collar.

In the position of the parts shown in the drawing the spring 20 merely bottoms the collar on the wall 16 and the terminal lower nose of the dependent pin is held spaced for a preset short distance from an adjacent abutment seat on the outwardly opening valve parts and the valve is held closed by a coil spring 23 surrounding the pin and bearing at opposite ends on the abutment seat and the underside of the partition wall 16. Thus a predetermined movement of the abutment seat against the elastic force of the spring 23 must take place to bring the abutment seat into contact with the nose of the pin

before thrust can be transmitted through the pin for supplementing the resistance of the primary spring 23 by the added resistance of the secondary spring 20.

The pin abutment seat referred to consists of the base of a cup-shaped stamping 24 telescoped for compactness about the spring 23 and the dependent pin 18 and which cup together with a surrounding corrugated flexible wall or bellows 25, an enclosing shell 26 and a dependent dead end tube or bulb 27 constitute the main parts of the floating valve normally seated on the shoulder 6 to seal the engine cooling system. The large diameter upper shell 26 above the valve seat 6 and the smaller diameter lower tube projected below the valve seat may be considered as a one-piece unit, but for convenience of manufacture they are shown as separately formed parts soldered together between the inturned annular flange at the bottom of the shell and the outturned annular flange at the top of the tube and which flanges afford an intermediate shoulder to seat on the casing shoulder 6. A sealing gasket 28 is positioned under the intermediate casing shoulder by a flanged sleeve 29 press fitted or soldered on the wall of the tube 27. The inside of the intermediate shoulder, through the outturned flange of the tube 27, has fastened securely thereto the lower end of the expansible bellows 25, whose opposite or free end is secured to an annular outturned flange of the cup 24 which affords a header closing the interior chamber of the bellows. Maximum expansion of the bellows is limited by an abutment ring 30 carried at the top of the shell 26 for contact with the outturned flange of the cup 24. Contraction of the bellows is limited by contact of the base of the cup or header 24 with a ported and flanged bushing 31 fitted to the intermediate shoulder and within the top of the dependent tube 27. Raised radial ribs on the upper surface of the bushing 31 seat the bottom of the cup 24 and afford between them openings to insure communication at all times of the bellows chamber through the ported bushing 31 with the chamber interiorly of the tube 27. This chamber space is about two-thirds filled with liquid of a type whose boiling point substantially corresponds with the cooling system liquid. For convenience the same liquid solution can be used and the liquid is introduced prior to installation through an opening in the bottom of the tube, the opening thereupon being sealed by the plug 32.

In the event system internal pressure decreases below atmospheric pressure then external air pressure will unseat the by-pass valve 8 as the small force of the light spring is overcome for substantially balancing the pressures. Internal system pressure in excess of external pressure will act on the underside of the outwardly opening valve to lift it from its seat 6. With the parts positioned as illustrated the differential pressure needs to overcome the downward force exerted by the primary spring 23. A drop in external pressure, as occurs in flight from sea level to higher altitude, will be compensated for by bellows expansion since pressure within the bellows acting on the underside of the header 24 will exceed external pressure on the upper surface of the header. Expansion of the bellows deflects the spring 23 and prevents unseating of the valve at a lesser internal pressure. Thus even though the differential in pressure decreases the internal system

pressure will be substantially unaffected by the drop in external pressure.

The bellows will respond not only to variations in atmospheric pressure but also to system temperature changes inasmuch as the dependent dead end tube 27 projects a considerable distance below the closure valve and exposes a large wall area to the system contents within the space 2 for the transfer of heat between the system liquid and the liquid interned within the bellows and its bulb chamber. Thus vapor pressure within the bellows tends to expand the bellows against the resistance of both the spring force and the external atmospheric pressure and the extent of expansion for a given bellows pressure will depend upon the value of external pressure so that changes in both temperature and altitude are compensated for in the operation of the valve in controlling the system operating pressure for the different operating conditions.

With temperature compensation the cooling system will not be subjected to any higher differential pressure than is necessary to produce adequate cooling whereas conventional valves heretofore used have been designed to relieve at a given high pressure and therefore pressure builds up although the temperature condition of the engine may not require the higher pressure for cooling purposes. Considering that the primary spring 23 can be overcome by a system pressure of seven pounds per square inch and when supplemented by the secondary spring 20 that the combined resistance of thirty pounds per square inch is offered to unseating of the valve, and assuming the use of a coolant whose boiling point at sea level is approximately 220° F., then the operation of the valve from the cold closed position shown will be substantially as follows:

The first stage of operation deals with cooling system temperatures of about 220° F., or less. Under this condition the exhaust valve will always open to relieve system pressure surge at seven pounds per square inch as determined by the spring 23, because under this condition the bellows is fully contracted. As the vapor pressure builds up within the bellows the header 24 moves toward the abutment nose of the pin 18 which it strikes in the neighborhood of 225° F. With bellows expansion the relief pressure will always be approximately seven pounds greater than the vapor pressure in the cooling system because any increase in pressure on the underside of the exhaust valve is now compensated for by a corresponding increase in vapor pressure in the bellows. After the header 24 contacts the pin 18 its further upward movement will be against the combined thirty pound pressure of both springs 23 and 20 and which pressure must be exceeded in order to unseat the valve. The bellows will continue to expand as the vapor pressure builds up until the header strikes the limit stop 30 which takes place at approximately 260° F. After the bellows expansion is thus restricted further increase in vapor pressure within the bellows will not serve in holding the valve shut and therefore the further pressure build-up within the system will soon overcome the seven pound differential which existed just prior to the contact with stop 30 and the excess pressure will be relieved by additional compression of the blowoff springs.

From the above description it will be seen that until the system pressure approaches the given absolute relief pressure any sudden surge

of pressure will be exhausted at a seven pound build-up so as to relieve the system parts from the explosive stress of violent ebullition.

We claim:

1. In a compensating safety pressure regulator for closed systems, a casing having a blow-off passage therethrough, a partition fixedly mounted in the casing, a pressure responsive expansible bellows containing a vaporized liquid and being floatingly housed by the casing on the innermost side of the fixedly mounted partition and having its inner end wall normally seated over the blow-off passage as a valve seal therefor, and a pair of tandem springs on opposite sides of the fixed partition, that on the inner side of the partition exerting its force at all times on the outer end wall of the bellows and that on the outer side of the fixed partition having its range of expansion limited by the fixed partition so as to exert its force on the outer end wall of the bellows only after a predetermined travel of said outer end wall.

2. An atmospheric pressure and system temperature compensated safety pressure regulator for closed systems, including a valve housing open to atmosphere and having a shouldered passage-way therethrough, a partition fixed therein, a pressure responsive expansible bellows containing a vaporized liquid and being floatingly contained in said housing with its inner end wall cooperating with the shouldered passage as a closure valve therefor, spring means bearing at one end against said fixed partition and bearing at its opposite end on the outer end wall of the expansible bellows, supplementary spring means having a stop on the partition for the free end thereof and an actuating plunger for said free end to transmit force between the supplementary spring and the last mentioned end wall of the expansible bellows only after a predetermined range of end wall movement.

3. For use with an engine cooling system, closed to atmosphere, a pressure relief device comprising a casing having a passage therethrough providing an inlet and an outlet, an expansible bellows contained floatingly within the casing with one end cooperating with a valve seat to close said passage, a rigid bulb projected from said end with its terminal projecting through the inlet, the interior of the bulb and the bellows being open to one another and partly filled with a vaporizable liquid, a spring thrust receiving seat fixed to the other end of the bellows, a primary spring bearing at one end on said bellows thrust receiving seat and being active at all times to offer continuous spring resistances to expansion of the bellows as well as bodily movement of the bellows from said valve seat, a partition plate immovably fixed on the casing and on which the opposite end of the spring bears at all times, a secondary spring active only after a predetermined deflection of the primary spring to supplement the continuous force exerted by the primary spring on said bellows, a limit stop abutment for the free end of the secondary spring bottoming on said partition plate, and a thrust transmitting pin screw threadedly mounted in said abutment for axial adjustment of pin position and projected from the abutment through said plate to terminate in position to be con-

tacted by the spring thrust receiving seat of the bellows after said predetermined deflection of the primary spring.

4. For use with an engine cooling system, closed to atmosphere, a pressure relief device comprising a casing having a passage therethrough providing an inlet and an outlet, an expansible bellows contained floatingly within the casing with one end cooperating with a valve seat to close said passage and having a bulb projecting through the inlet, the interior of the bulb and the bellows being open to one another and partly filled with a vaporizable liquid, a spring thrust receiving seat fixed to the other end of the bellows, a primary spring bearing at one end on said bellows thrust receiving seat and being active at all times to offer continuous resistance to expansion of the bellows as well as bodily movement of the bellows away from said valve seat, a partition in the casing on which the opposite end of said spring bears and secondary spring means having one end fixed in relation to the casing and its other end free for deflection but bottoming on said partition as a limit expansion stop therefor and having a thrust mating extension for cooperation with said thrust receiving seat after predetermined deflection of the primary spring.

5. In a pressure relief device, a ported valve 30 casing having an inlet and an outlet and a valve seat surrounding the inlet, the wall of said casing having an integral hollow offset in one side communicating with the inlet below and in bypass relation with the valve seat, an inwardly 35 opening check valve housed within said wall offset, an outwardly opening valve contained within the casing for engagement with said seat, a vaporizable liquid containing expansible bellows carried by said outwardly opening valve, spring means exerting its force at all times on the bellows and acting continuously to resist expansion thereof and acting through the bellows to yieldingly seat the outwardly opening valve and additional spring means having a limited 45 range of expansion with its deflectable free end constructed and arranged to bottom on the casing for an expansion stop and to be engaged by the bellows only after a predetermined expansion thereof for additional resistance to further expansion of the bellows and unseating 50 of the outwardly opening valve.
